UNITED STATES PATENT OFFICE.

FREDERICK A. LESTER, OF CHICAGO, ILLINOIS.

DOOR-ACTUATING MECHANISM.

1,242,001.

Specification of Letters Patent.

Patented Oct. 2, 1917.

Application filed February 9, 1915. Serial No. 7,176.

To all whom it may concern:

Be it known that I, FREDERICK A. LESTER, a citizen of the United States, residing at Chicago, in the county of Cook and State 5 of Illinois, have invented certain new and useful Improvements in Door-Actuating Mechanism, of which the following is a full, clear, and exact specification, reference being had to the accompanying drawings, 10 forming a part hereof.

This invention relates generally to door actuating mechanism, and has reference more particularly to that type of door actuating mechanism designed to close a grain 15 door, or the like, and to retract it from its closed position in the doorway opening to an open or partially open position opposite the doorway opening.

My invention has for its principal objects 20 to provide a simple, durable and efficient device of the character described which can be readily and cheaply applied to the door and doorway frame at a minimum cost; and furthermore to produce a device in 25 which the component parts are compactly arranged and wherein the manually operable member of the device is adapted to move in substantially the same plane as that of the door face and thereby permit 30 full use of the same under circumstances where working space is limited.

These, together with such other objects as may hereinafter appear, or are incident to my invention, I attain by means of a construction illustrated in preferred form in 35 the accompanying drawings, wherein:—

Figures 1 and 2 are views in side elevation and in section of the preferred embodiment of my improved device as applied 40 to the grain door of a railway box car, when in closed position;

Figs. 3 and 4 are similar fragmentary views of the invention shown in Figs. 1 and 2, showing the door in open position;

45 Figs. 5 and 6 represent detailed views of the sealing element, and

Fig. 7 represents a perspective view of the door when opened by the actuating device.

For purposes of illustration, I have 50 shown my invention as applied to a grain door of the type shown and described in my co-pending application, Serial No. 874,640, and which is preferably set in flush, though not necessarily so, with the door-

way frame, and pivotally or movably hung 55 from the frame at or near its upper end, for example in the manner shown and described in said co-pending application, so as to permit its retraction by the door actuating mechanism to a new and partially 60 open position opposite the door opening. It will be understood that when so moved to this partially open position, the grain near the door discharges, and this discharge 65 of grain is guided by the door through the opening thus provided, in the manner pictorially shown in Fig. 5, into the grain chute of the elevator, thus ultimately relieving the pressure against the door and so as to permit its movement clear of the doorway 70 opening, whereupon the unloading operation may be completed by the employment of grain scoops or other unloading devices.

Referring to the drawings, the numeral 75 6 indicates the door, and 7 the doorway frame. As previously indicated, my invention more particularly resides in the door actuating device, which preferably comprises the door-frame engaging member A 80 and the manually operable lever member B, both of which co-operate to retract the door to its partially open position and to return it to its closed position where it is maintained against opening movement. The 85 door-frame engaging member A embodies a shaft body member mounted on the door for axial movement in eyes 9 and extends horizontally across the door to terminate in the bent end portions 8. Intermediately of the 90 eyes 9, the shaft is formed with an offset or crank 10, which is offset substantially in the opposite direction to that of direction of bend in the end portions; and in the position of the crank as shown in Figs. 1 and 2, the 95 bent end portions are designed to extend upwardly to engage with the keepers 11 which are bolted to the doorway frame at either side of the door.

Pivotedly mounted on the door adjacent 100 the member A, as at 12, is the actuating member B provided at its upper end with a head 13 formed with a slot 14 so as to loosely and slidably engage the crank 10, and whose lever arm or rod 15 depends from 105 its pivot 12 to lie up close with the door for free swinging movement in a vertical plane whereby to operate the member A.

The normal relative arrangement of the end portions 8 and crank 10 is preferably such that they extend respectively above and below the axial line of the shaft when positioned as shown in Fig. 1.

From the description thus far made, it will be obvious that in order to retract the door to its partially open position so as to obtain the initial grain discharge, the crank 10 is forced upwardly on a short arc by manipulation of the lever rod 15 to the right on its pivot 12, consequently depressing the end portions 8 which working against the bases of the keepers 11 force the door outwardly to the position shown in Figs. 3, 4 and 7, where they serve to support the door in its new position.

With a view to providing a sealing device for the door and as a means for retaining the lever rod in position when the door is closed, I have shown a preferential construction embodying a slidable lock bar 16 formed at one side of its median line with a vertical slot 17 which terminates at its upper end in a lateral 17^a, in which latter a headed pin 18 rigid with the door normally seats to carry the bar and upon which it moves. The lower end of the bar has an offset tongue 19 adapted to freely enter and seat in an aperture 20 formed in the threshold plate, and further is suitably provided with an outwardly extending sealing flange 19^a. If desired, a recess 21 may be provided at the rear of the bar, which opens into the space back of the offset tongue in which recess a stud 22 is adapted to travel, normally being seated at its upper terminal and in substantial vertical alinement with the pin 18 in the lateral 17^a and below it, as more clearly shown in Figs. 5 and 6.

This lock bar 16 is positioned adjacent the lower end of the lever rod 15, and in its line of travel, the rod being outwardly bent near said end to constitute a handhold 23, and is also formed with an angular extension 24 over which the tongue 19 normally extends to hold the rod in locked position. A complementary member to the sealing flange 19^a may be mounted on the door, but by preference I show an angle bar 25 extending across and secured at or near the bottom edge of the door which is bent sufficiently away to permit the passage therethrough of the tongue 19 into the seat on aperture 20, the outwardly extending flange 25^a thereof and sealing flange 19^a being correspondingly apertured to receive the seal 26.

The limiting positions of the lever rod 15 are clearly shown in the drawings. When it is desired to open the door, the seal is first broken, then the slotted bar is moved upwardly and to the left on the pin 18 into the clearance provided by the handhold 23, and at the same time disengaging from the

bent end 24, thus permitting the free movement of the lever rod 15 and the opening of the door as already described. To close the door, the lever rod is given reverse movement, whereupon the end members 8 engage 70 the keepers 11, and the lever rod is then locked by the sealing device. The terminals of the end members 8 are preferably curved as shown, in order to facilitate their entrance into and engagement with the eyes of the 75 keepers.

In order to properly limit the movement of the door when moving to this new position, I preferably provide the brackets 27 secured to the door frame below the threshold and adjacent the angle bar 25, and whose stop flange 28 is spaced sufficiently away to permit this movement and against which the lower edge of the door is intended to take when the door is so moved. This bracket 80 carries a swinging jaw 29 which may be swung out of the way when the door is to be opened, and returned to a wedging position against the flange 25^a, as more clearly shown in Fig. 2, whereby to relieve the operating parts from undue strain which might be placed upon them by load pressure.

One of the principal advantages attained by my improved construction is that the movable members are compactly arranged so as to take up but little space during their operation, and in this connection I have special reference to the member B whose movement is in a substantially vertical plane, this being particularly advantageous where 95 working space is limited, such as between cars, or between a car and an elevator, as will be readily understood by those skilled in the art.

I do not intend to restrict myself to the 105 exact arrangement of the parts nor to the precise details of construction as shown, for it is obvious that variations therefrom may be made without in any way departing from the spirit and scope of my invention as 110 pointed out in the appended claims.

Having thus described my invention and illustrated its use, what I claim as new and desire to secure by means of Letters Patent, is the following:

1. In combination, a door actuating mechanism including a lever mounted for movement in the plane of the door and having a portion thereof bent away from the door to provide a clearance therebetween, a locking device normally locking with the lever and disposed in the path of said lever, said device being mounted on said door for swinging movement into said clearance and out of the path of travel of said lever as the lever is actuated.

2. The combination with a door, of a door actuating member mounted for swinging movement in the plane of the door, and a locking device normally positioned in the 130

path of and locking with said lever to hold the same against movement in one direction, said device pivotally mounted on the door and slotted for slidable movement relatively of its pivot whereby to clear said actuating member and permit movement of the same in both directions.

In testimony whereof I have hereunto signed my name and affixed my signature in the presence of the two subscribed witnesses. 10

FREDERICK A. LESTER.
